ENGINE ACCESSORY

Romeo M. Nardone, Teaneck, N. J., assignor to
Joseph J. Mascuch, Maplewood, N. J.

Application December 9, 1947, Serial No. 790,588

3 Claims. (Cl. 248—2)

1

This invention relates to engine accessories, and particularly to the means for attaching and supporting an engine accessory.

Engine accessories such as starters, generators, compressors, etc., usually have a circular flange, called a mounting flange, adapted to abut a circular mounting pad provided on the surface of the engine housing, the engine pad being centrally apertured to permit the accessory main shaft, or engine shaft-engaging clutch to pass through. The engine pad is also equipped with studs spaced about its annular surface, and mounting of the accessory on the engine pad is effected by suspending the accessory flange, above referred to, on the projecting ends of these studs, the accessory flange having stud-receiving holes to make such suspension possible. Retaining nuts are then threaded to the stud ends to hold the accessory in the suspended position.

The arrangement above described is quite satisfactory, so long as the diameter of the accessory flange is such as to cause its stud-receiving holes to align accurately with the stud circle on the engine pad; but as engine pad stud circles are of graduated diameters, according to the capacity and style of engine-stud circles of five inch diameter being used as commonly as those of $5\frac{3}{4}$ inch diameter—an accessory equipped with a mounting flange whose mounting holes are on a $5\frac{3}{4}$ inch circle cannot be attached to an engine pad having a five inch diameter stud circle. As a consequence, it has heretofore been necessary to maintain a double stock supply of accessories at all engine servicing depots, in order to meet the dual conditions just described.

An object of the present invention is to provide means whereby all engine accessories will be attachable to both sizes of engine pads, thus eliminating all "mis-fit" problems.

A second object of the invention is to provide means for securing the accessory to the engine pad in such manner as to permit subsequent removal without disturbing the stud nuts.

Another object is to provide a single securing means to replace the multiple securing means constituted by the studs and fastening nuts therefor; the studs and stud nuts being retained, however, as locating, supporting, and torque reaction receivers.

These and other features of the invention will be further described with reference to the accompanying drawings illustrating the preferred embodiment of the invention. It is to be understood, of course, that other embodiments are pos-

2

sible, and that the invention is limited only by the scope of the appended claims.

In the drawings:

Fig. 1 is a view, partly in elevation and partly in central vertical section, of the forward section of an engine starter, showing also the novel attaching and supporting means as they appear in relation to an engine mounting pad of the so-called "six inch" size;

Fig. 2 is a transverse sectional view along the line 2—2 of Fig. 1;

Fig. 3 is a view similar to Fig. 1, but in relation to an engine mounting pad of the "seven inch" size; and

Fig. 4 is a transverse sectional view along the line 4—4 of Fig. 3.

In Fig. 1 there is indicated, at 5, a portion of an engine mounting pad equipped with the usual studs 6 that normally receive the starter flange 7 and fastening nuts; but in accordance with the present invention there is associated with the starter flange 7 and the engine pad 5 a pair of complementary securing rings 8 and 9, having inter-engaging threaded portions 10 and 11, respectively; and the starter flange has two sets of openings 12 and 13, the openings 12 permitting the said flange to be pushed up against the securing ring 8 without interference from stud nuts 14, and the openings 13 permitting the flange 7 to be similarly pushed into position without interference from stud nuts 15, the latter being shown in Figs. 3 and 4 as the fastening means for ring 8 when the engine stud circle is of a $5\frac{3}{4}$ inch, rather than a five inch, diameter.

Thus, by the use of the complementary securing rings 8 and 9, and the specially constructed starter flange 7, with its two sets of openings 12, 13, it becomes possible to fit such a flange into position on either a six or a seven inch mounting pad, and to lock it in said position simply by threading ring 9 onto the receiving rim 10 of the ring 8; the inner end of the ring 9 being adapted to exert an axially directed thrust on the rim 16 of the starter flange 7, to secure it in position.

Conversely, whenever it becomes necessary to remove the starter for any reason, the only operation required is to unscrew the ring 9 from rim 10, whereupon the entire starter may be withdrawn from the engine pad by simply drawing flange 7 back over the nuts 14 (or 15, Fig. 3, as the case may be, depending upon whether a six or a seven inch pad is involved); there being no necessity of disturbing the stud nuts, studs, or securing ring 8 on any such occasion, as openings 12 and 13 are large enough to prevent interfer-

ence between said openings, on the one hand, and nuts 14 and 15, on the other. In fact, after their initial installation, the studs, stud nuts and securing ring 8 may be considered to be permanently attached elements of the engine, along with the mounting pad 5 (or 5a, Fig. 3).

Since the openings 12, 13 are large enough to clear the corners of the stud nuts, it follows that they are considerably larger than the diameter of the studs themselves. It is, therefore, necessary to provide spacers, as at 21, to take up the difference in diameters, as between flange openings and studs, also to take up the space, in an axial direction, as between the stud nuts and the ring 8. These spacers 21, therefore, take axial thrust as well as the torque reaction.

It will be understood that flange 7 is integral with the housing 22 of the starter or other engine accessory to which the invention is to be applied. The starter illustrated has a rotatable clutch element 23 of the three-tooth type, the teeth being so formed as to be drivably engageable with another clutch element (not shown) carried by the engine shaft, provided the engaged clutch element has the same number of teeth, or some integral multiple thereof.

I claim:

1. In combination with an engine housing having an accessory mounting pad, a series of studs secured to said pad and having their axes disposed in a circle whose center lies on the longitudinal axis of the accessory to be mounted thereon, and means for mounting on said studs an accessory of a standard diameter, said mounting means including a flange integral with said accessory and provided with plural circular rows of openings, which rows have diameters corresponding to those of different sizes of engine pads, said flange being further provided with a rearwardly turned rim at its periphery, and

means including a pair of complementary elements, one interposed between said mounting pad and said flange, and the other secured thereto and abutting said rim to hold said flange in position upon said studs.

2. In combination with an engine housing having an accessory mounting pad, a series of studs secured to said engine pad and having their axes disposed in a circle whose center lies on the longitudinal axis of the accessory to be mounted thereon, fastening members threaded to said studs, and means distinct from said fastening members for securing said accessory to said engine pad, said securing means including a pair of complementary elements, one of said complementary elements being interposed between said engine pad and said fastening members, and permanently held thereby.

3. Apparatus as defined in claim 2, wherein the other of said complementary elements coacts with said first complementary element to constitute the sole securing means for the accessory.

ROMEO M. NARDONE.
